UNITED STATES PATENT OFFICE.

HANS EWALD BUKOP, OF BERLIN, GERMANY, ASSIGNOR TO GESELLSCHAFT FÜR DRAHTLOSE TELEGRAPHIE M. B. H. HALLESCHES, OF BERLIN, GERMANY, A CORPORATION OF GERMANY.

VALVE AMPLIFIER.

Application filed September 3, 1921, Serial No. 488,472, and in Germany August 9, 1917.

(GRANTED UNDER THE PROVISIONS OF THE ACT OF MARCH 3, 1921, 41 STAT. L. 1313.)

This invention relates to a valve amplifier in the form of a three-electrode vacuum tube, and an object of the invention is to enable the voltage of the grid of the tube to be accurately adjusted to the optimum value.

In the drawing,

Fig. 1 shows a vacuum tube arrangement in which the invention may be employed, 10 and

Figs. 2 and 3 show vacuum tube arrangements of slightly different form embodying the invention.

In the operation of an amplifying tube 15 with a glow-cathode, it is necessary to impress upon the grid a certain voltage, on the average 2 or 3 volts negative, relatively to the cathode. A simple means to bring about this negative voltage of the grid with respect to the cathode is to put a series 20 resistance R into the heating circuit of the cathode and to branch off therefrom the grid-conductor GL , Fig. 1. If, as a series-resistance, a so-called self-regulating iron 25 resistance E is used, Fig. 2, only the ends of the resistance will be accessible. There will then be obtained too small or too great grid-voltages. The present invention enables substantially the optimum value of the 30 grid voltage to be obtained, and to this end there is provided in parallel with the iron resistance E a resistance R , from which the grid-conductor is branched off and which is very great compared with the resistance E . 35 Of course, the grid-voltage may then be caused to be always near the optimum value, but it is not absolutely constant, since it is proportional to the voltage at the iron resistance. This fluctuation can be reduced 40 to an unnoticeable degree by placing between the cathode and the iron resistance, a second constant resistance R_2 , Fig. 3.

The self-regulating resistance mentioned above, is a resistance made up of a material 45 whose resistivity rises sharply with increase in current therethrough, thereby acting automatically as a current limiting device. In this sense this term is used in the appended claims.

Having described my invention, what I claim is:

1. A valve amplifier comprising a cathode

filament and a grid, a self-regulating resistance in the heating current circuit of the filament, a constant resistance arranged in parallel with said first-mentioned resistance, and a conductor for the grid connected adjustably to the last-mentioned resistance.

2. A valve amplifier comprising a cathode filament and a grid, a source of energy in the heating current circuit of the filament, a self-regulating resistance inserted in said circuit between the filament and the negative terminal of said source of energy, a constant resistance arranged in parallel with said first-mentioned resistance, and a conductor for the grid connected adjustably to the last-mentioned resistance.

3. A valve amplifier comprising a cathode filament and a grid, a self-regulating iron resistance in the heating current circuit of the filament, a constant resistance arranged in parallel with said self-regulating resistance and of great value as compared with the self-regulating resistance, and a conductor for the grid connected with said last-mentioned resistance.

4. A valve amplifier comprising a cathode filament and a grid, a self-regulating iron resistance in the heating current circuit of the filament, a constant resistance arranged in parallel with said iron resistance, a conductor for the grid adjustably connected with the last-mentioned resistance, and a second constant resistance arranged in the filament heating circuit in series with both of said first-mentioned resistances.

5. A valve amplifier comprising a cathode filament and a grid, a self-regulating iron resistance in the heating current circuit of the filament, a constant resistance arranged in parallel with said iron resistance, a conductor for the grid adjustably connected with the last-mentioned resistance and a second constant resistance arranged in the filament heating circuit between the iron resistance and the filament and in series with both of said first-mentioned resistances.

6. In combination, an electron discharge device having a cathode and a control electrode, a self-regulating resistance in the heating current circuit of said cathode, a constant resistance arranged in parallel to said self-regulating resistance, and a conduc-

2
tor for the control electrode connected to a point on said constant resistance.

7. In combination, an electron discharge device having a cathode and a control electrode, a self-regulating resistance in the heating current circuit of said cathode, a constant resistance in parallel with said self-regulating resistance, a conductor for the

control electrode connected to a point on said constant resistance, and a second constant resistance in the heating current circuit in series with both said first-mentioned resistances. 10

In testimony whereof I affix the signature.

HANS EWALD RUKOP.
